UNITED STATES PATENT OFFICE

155,026

DESIGN FOR A LIST FINDER

William C. Nein, New York, N. Y.

Application November 22, 1947, Serial No. 142,734

Term of patent 14 years

(Cl. D74—5)

To all whom it may concern:

Be it known that William C. Nein, a citizen of the United States of America, residing at 1475 Popham Ave., New York city, in the county of Bronx and State of New York, has invented a new, original, and ornamental Design for a List Finder, of which the following is a specification, reference being had to the accompanying drawing, forming part thereof.

Fig. 1 is a perspective view of a list finder, showing my new design in closed position; and

Fig. 2 is a perspective view of Fig. 1 in open position. The side not shown is the same as the one shown and the rear portion is substantially plain.

I claim:

The ornamental design for a list finder, as shown and described.

WILLIAM C. NEIN.
